US00D437610S

(12) **United States Design Patent**
Gasvoda et al.

(10) **Patent No.:** **US D437,610 S**
(45) Date of Patent: **** Feb. 13, 2001**

(54) **FLUID CONTAINER**

(75) Inventors: **Eric L. Gasvoda, Salem; Susan M. Hmelar, Corvallis, both of OR (US)**

(73) Assignee: **Hewlett-Packard Company, Palo Alto, CA (US)**

(**) Term: **14 Years**

(21) Appl. No.: **29/086,375**

(22) Filed: **Apr. 9, 1998**

Related U.S. Application Data

(63) Continuation-in-part of application No. 08/566,521, filed on Dec. 4, 1995, now abandoned, and a continuation-in-part of application No. 08/868,773, filed on Jun. 4, 1997, and a continuation-in-part of application No. 29/055,382, filed on Jun. 5, 1996, now Pat. No. Des. 416,573.

(57) **CLAIM**

We claim the ornamental design for a fluid container, as shown and described.

DESCRIPTION

FIG. 1 is a top, front, and left side perspective view of a fluid container of our new design;

FIG. 2 is a front elevational view thereof, the rear being identical;

FIG. 3 is a left side elevational view thereof, the right view being identical to the left;

FIG. 4 is a top plan view thereof;

FIG. 5 is a bottom plan view thereof;

FIG. 6 is a top, front, and left side perspective view of a second embodiment of FIG. 1;

FIG. 7 is a front elevational view of FIG. 6, the back view being identical to the front;

FIG. 8 is a left side elevational view of FIG. 6;

FIG. 9 is a right side plan view of FIG. 6;

FIG. 10 is a top plan view of FIG. 6; and,

FIG. 11 is a bottom plan view of FIG. 6.
